UNITED STATES PATENT OFFICE.

HENRY ANDREW FENSKY, OF LADYSMITH, WISCONSIN.

PULP-FEED REGULATOR.

1,397,415.

Specification of Letters Patent. Patented Nov. 15, 1921.

Application filed August 14, 1920. Serial No. 403,534.

To all whom it may concern:

Be it known that I, HENRY A. FENSKY, a citizen of the United States, residing at Ladysmith, in the county of Rusk and State 5 of Wisconsin, have invented new and useful Improvements in Pulp-Feed Regulators, of which the following is a specification.

This invention relates to weighing means for pulp machines, the principal object of the 10 invention being to provide means for delivering a stream of pulp of uniform weight to the mixing box from the stuff box, the weight of the stream being kept uniform by the automatic action of said means.

15 Another object of the invention is to provide means whereby the stream of pulp may be kept at any desired weight.

This invention also consists in certain other features of construction and in the 20 combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:—

30 Figure 1 is a side view of the invention.

Fig. 2 is a front view.

Fig. 3 is a horizontal section on line 3—3 of Fig. 1.

Fig. 4 is a detail view of the hopper.

35 Fig. 5 is a view of the gage or spout member.

Fig. 6 is a view of the dripping pan or spout.

In these views 1 indicates the stuff box to 40 which the pulp is supplied by the inlet pipe 2 and 3 indicates the outlet pipe or overflow. 4 indicates a valve for controlling the outlet pipe 3. A port 5 is formed in the upper part of the box 1 and a reinforcing 45 strip 6 is placed on the front of the box and this strip has guideways therein on each side of the port. The gage or spout member 7 is slidably mounted in said guideway and said gage has an opening 8 in its upper part 50 for registering with the port when the gage is in its lower position. A spout 9 is carried by the gage for receiving the material passing through the opening 8. A stem 10 is formed on the upper end of the gage having an eye 11 in its upper end and a weight 55 rest 12 is carried by said stem. A frame 13

is secured to the strip 6 and bearings 14 are formed in the outer parts of said frame to receive the U-shaped member 15. Uprights 16 are carried by the frame 13 and these uprights support a pulley 17. A cable 18 has one end connected with the eye 11 and its other end connected with the cross piece of the U-shaped member 15.

A hopper 19 is carried by the ends of 65 the U-shaped member 15 and this hopper receives the lower end of spout 9 so that the material flowing through said spout will be received in the hopper. This hopper is of substantially the shape of an inverted cone 70 with an outlet spout 19' at its lower end from which the pulp will drop into the mixing box 20 or to any other place where wanted. The hopper is provided with a partition 21 which leaves a space between its lower end 75 and the adjacent part of the hopper so that the material in the hopper can slowly pass through this space and also over the top of the partition. This will agitate the pulp in the hopper. The opening leading to the 80 outlet spout 19' is controlled by a gate or valve 22, the stem 23 of which passes out of the top of the hopper where it is provided with a handle. By this gate the gage of the opening can be regulated so as to control 85 the flow of pulp from the hopper.

As long as the valve 4 is open the stock will flow into box 1 through the pipe 2 and out again through pipe 3. When the valve 4 is closed, however, the stock will rise in the 90 box 1 and when it reaches the port 5 it will pass through the same and through the opening in the gage and drop from the spout 9 into the hopper and from the hopper drop into the mixing box. A weight is placed on 95 the rest 12 before the valve is closed and this weight will then force the gage to the bottom of the guideways and open the port 5 to its full extent. This downward movement of the gage will raise the hopper 19. 100 The weight of the material dropping into hopper will lower the same and thus raise the gage and partly close the port, the extent of movement of the parts corresponding to the size of the weight placed on the rest. 105 For instance, if the stock is being delivered to the box 1 at the rate of 80 pounds a minute and a 40 pound weight has been placed on the rest, the stream of pulp dripping into the hopper at first will be the same as has 110 been delivered to the box. That is, at the rate of 80 pounds a minute. This weight

will force the hopper downwardly to raise the gage until the stream dropped into the hopper will be reduced to 40 pounds. In other words, the weight of the stream passing through the reduced port will be the same as that of the weight on rest 12 so that by placing different sizes of weights upon said rest the weight of the stream of pulp passing into mixing tank 4 can be regulated and this weight will be kept uniform automatically by the device. As is well understood, the different kinds of wood from which the pulp is made has different weights and the pulp will vary in weight according to the kind used. By the use of my machine, however, the flow will be so regulated that a stream of the same weight will be discharged into the mixing box. The paper made by the pulp handled by my machine will be of uniform weight as the pulp is weighed before the paper is made.

The adjustment of the gate in the hopper will also act to regulate the weight of the pulp. The long spout will act to prevent splashing of the pulp in the hopper.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. In combination with a stuff box and mixing box of a paper pulp apparatus, a gage plate for controlling the outlet port of the stuff box, a spout on said gage plate, a hopper for receiving the pulp in said spout and directing it into the mixing box, a slideable frame connected with the hopper, a pul-

ley, a cable connecting the slideable frame with the gage plate and passing over said pulley and a weight rest connected with the gage plate.

2. A device of the class described comprising a tank, having an outlet port therein, a gage plate controlling said port, a spout on the gage plate, a hopper for receiving the material from the spout and delivering it to the point of use, a slideable frame supporting said hopper, a pulley, a cable passing over said pulley and having one end connected with the gage plate and its other to the slideable frame and a weight rest connected with said gage plate.

3. An apparatus of the class described comprising a tank having an outlet port therein, a guideway formed on each side of said port, a gage plate slidably mounted in said guideway, a spout thereon, a hopper for receiving the material flowing through said spout, a mixing box for receiving the material from said hopper, a slideable frame supporting said hopper, a pulley, a cable passing over the same and having one end connected with the gage plate and its other to said frame and a weight rest connected with said gage plate.

4. An apparatus of the class described comprising a tank having an outlet port therein, a gage plate for controlling said outlet port, a spout carried by said gage plate, a hopper into which the spout projects, flexible means for connecting the gage plate with the hopper, a pulley over which said flexible means pass, a weight connected with said gage plate, said hopper having an outlet port therein and a gate for controlling said port.

In testimony whereof I affix my signature.
HENRY ANDREW FENSKY.
